UNITED STATES PATENT OFFICE

OCTAWE LE CLAIR VALENTINE, OF BRIDGEPORT, CONNECTICUT, ASSIGNOR, BY MESNE ASSIGNMENTS, TO THE BAY COMPANY, OF BRIDGEPORT, CONNECTICUT, A CORPORATION OF DELAWARE

BANDAGE SELVAGING MACHINE

Application filed May 31, 1928. Serial No. 281,985.

This invention relates generally to a bandage selvaging machine, and more particularly to a device adapted to be attached to the ordinary bandage slitting machine and to 5 operate in conjunction therewith to produce nonraveling selvages along the edges of each bandage turned out by the machine.

A well recognized objectionable feature 10 of surgical bandages has been their tendency to ravel and fray at the edges. To obviate this difficulty, by providing bandages with woven selvages, is impractical, and to apply an adhesive substance to the edges produces a bandage which is not only obnoxious to 15 apply but is decidedly unsanitary.

Accordingly, the principal object of this 20 invention is to provide a machine for forming non-raveling selvages in fibrous material, particularly along the edges of bandage strips severed from wide sheets or rolls of surgical gauze; and to provide a machine of this character, which is simple in construction, efficient in operation, inexpensive to employ, and preferably capable of quick 25 and easy adjustment to operate effectively on strips of different widths.

A further object of this invention is to 30 provide a machine of the character described, and one which may be organized as an attachment adapted to be associated 35 with a slitting machine, without requiring any alteration or modification of the slitting machine other than the hooking up of the selvaging attachment thereto.

Other objects of this invention will be in 40 part obvious and in part pointed out herein-after.

The selvaging machine with which this 45 application is concerned acts on the edges of the gauze strips to destroy the tensile strength of the threads and to create a pulped or friable condition in the material, at the same time uniting the material at intersections so intimately as to defy separation. 50 Since intersections remain fast the threads inwardly thereof cannot pass by or ravel or fray from the strip. The force applied by the machine to effect the selvage condition referred to is believed to be in the nature 55 of a crushing, mashing and grinding action,

and is preferably applied by causing the edges of the strips to pass between two hard-surfaced rollers pressing together with resilient pressure.

In order that a clearer understanding of 55 this invention may be had, attention is hereby directed to the accompanying drawings, forming a part of this application and illustrating certain possible embodiments of this invention.

Referring to the drawings, Fig. 1 is a top 60 plan view of my selvage forming device attached to a bandage slitting machine, only a part of the bandage slitting machine being shown;

Fig. 2 is a transverse vertical sectional 65 view of my selvage forming device and the cooperating rolls of the bandage slitting machine, and is taken on line 2-2 of Fig. 1;

Fig. 3 is a diagrammatical illustration of 70 the roll driving means of the bandage slitting machine;

Fig. 4 is a detail view of the manual adjusting means for the selvaging rollers;

Fig. 5 is a plan view of one of the press- 75 ing rollers;

Fig. 6 is a perspective view of the completed bandage, showing the non-raveling selvages along the edges of the bandage; and

Fig. 7 is a detailed vertical cross-sectional 80 view of the supporting bar and guides therefor, taken on line 7-7 of Fig. 1.

Similar reference characters refer to similar parts throughout the several views of the drawings.

Referring to Figs. 1 and 2 of the drawings, fragmental parts of a bandage slitting machine are illustrated for the purpose of showing how my selvage forming machine may be attached to the ordinary bandage 90 slitting machine and how the pressing rollers of my selvaging machine cooperate more particularly with the backing or platen roll of the slitting machine to produce my bandages having non-raveling, unwoven selvages. 95 The supporting framework of the bandage slitting machine, shown fragmentally at 1, supports a second framework 2, which carries the operative elements. Suitable brackets 3, secured at each end of the framework 100

2, carry the platen roll and various guide rolls of the bandage slitting machine. The platen roll 4 is fixed to shaft 5 journaled in the brackets 3, and may be either made entirely of a hard metal, or surfaced with a hard material. Guide roll 6, fixed to shaft 7 journaled in the brackets 3, guides the bandage material 8 around the platen roll 4. The slitting rollers which cut the bandage material into suitable bandage widths and the pressing rollers, forming my unraveling selvage, operate upon the bandage material as it passes around the platen roll, in a manner to be henceforth described. The completed bandages 10, cut to suitable widths and selvaged, are then wound upon the bandage core 9, as clearly shown in Fig. 2. Suitable means are provided to cause the completed bandages to wind themselves smoothly and neatly on the bandage core 9. Thus a weight roll 11 may be provided, journaled in blocks 12 and 13 resting on the bandages being wound on the bandage core. The weight roll 11 is vertically movable, blocks 12 and 13 fitting within guide members 14 and 15 and vertically slideable therein. Bandage core 9 may also be positioned for vertical sliding movement in guide members 14 and 15, permitting the rolled bandages to rest on platen roll 4 and guide roll 16 while in the process of being wound. The means above described for obtaining a smoothly wound bandage is merely for purposes of illustration, and other means may be used for winding bandages on a core, within the contemplation of this invention.

The bandage slitting machine carries some slitting means, preferably slitting rollers 17, which cut the bandage material into strips as it passes around the platen roll 4. The slitting rollers 17 may be adjustably supported on arms 18 fulcrumed on a suitable support 19.

The selvaging mechanism comprises a plurality of selvaging rollers 20, for which roll 4 serves as a backing or platen. For each slitting roller carried by the machine, there is a corresponding selvaging roller positioned in alignment therewith. The selvaging roller, shown in Fig. 5 in enlarged scale, has a comparatively thin periphery 21, preferably slightly crowned, the sides 22 of the roller being tapered.

Each selvaging roller may be journaled on a pin 23 or each roller may be fixed to the pin and the pin journaled in slots 24 formed on the end of fork elements 25 and 26, as shown in Figs. 2 and 5. Fork elements 25 and 26 are suitably secured to an arm 27, as by welding. Each arm is fulcrumed within a saddle member 28, which saddles a supporting bar 29.

The supporting bar 29 extends the length of the slitting machine and supports the

arms 27 carrying the pressing rollers. To produce the best results, the supporting bar must be rigid, unbending and free from any tendency to buckle or sag. The supporting bar is, therefore, preferably made of metal and of large cross section. To give it additional rigidity, a reinforcing member 30 is secured, as by bolts 31, to one side of the bar and a truss rod 32 secured at its ends to the other side of the bar by bolts 33. A suitable adjusting means is provided for adjusting the trussing effect exerted by rod 32 on the supporting bar and for straightening out the supporting bar should it become warped. To this end, I provide a bolt 34 extending through the midsection of the rod, resting against the supporting bar, and cooperating with nuts 35 and 36, one on each side of the bar. As the bolt is turned to the right or left, a corresponding bending moment is exerted on the supporting bar to truss and adjust the bar as desired.

The supporting bar rests upon a shaft having body portion 37 which is eccentric with respect to its ends 38 and 39 which are journaled in suitable brackets, such as 40, secured as by bolts 41 to the framework 2 of the slitting machine. Shaft body 37 extends the length of the supporting bar. It will now be seen that, as the shaft 37 is rotated, the eccentric body of the shaft, by its eccentric movement, raises or lowers the supporting bar 29. A suitable follower 42 may be secured to the bottom of the supporting bar which directly contacts with the cylinder.

The supporting bar is guided for vertical movement between blocks at each end thereof. End portions 43 and 44 of the bar are provided with a vertical groove 45 along the forward face thereof. Each forward block 46 and 47 is provided with a cooperating lug 48 fitting within the groove, preventing longitudinal movement of the bar. Block 46 is secured in position by means of bolts 49 to support 50 of the machine, and block 47 is also secured by bolts 51 to support 52 of the machine. Rear blocks 53 and 54 fit smoothly against the back side of the bar, and are secured in a suitable manner to the parts 50 and 52 of the framework of the slitting machine. Thus it is seen that the supporting bar is guided for vertical movement, with means provided to raise and lower the same to move the selvaging rollers toward and away from the platen roll.

To rotate the eccentric shaft 37, a hand crank 55 may be attached to its end 38, which extends beyond the block 40 in which it is journaled. To retain the supporting bar in the desired raised position, a pawl and ratchet arrangement is provided. Pawl 56 is fixed to rod 57 journaled in a suitable manner to the framework of the machine. The dog end 58 of the pawl en-

gages with the teeth of the ratchet wheel 59 fixed to shaft end 38, and holds the supporting bar in the vertical position to which it is raised by the hand crank. A reinforcing tie rod 60 and stiffener 61 may be used to connect the brackets 40 at each end of the machine to give rigidity and strength to the whole.

Means are provided to hold the selvaging 10 rollers against the platen roll with resilient pressure. An angle bar 62 extending the length of the machine is secured to posts 63, one at each end thereof. The lower end of each post is journaled to a pin 64 carried by a bracket 65 attached to the lower framework 1 of the slitting machine. Link members 66, journaled at one end to the rod 57, have an elongated slot 67 at the other end thereof. A key bolt 68 passes 20 through each slot and screws into a post member 63, permitting the end of each post to be fixed to the corresponding link member at any point along the slot. By this arrangement it is seen that the angle bar 25 62 can be swung in an arc outwardly and downwardly, or vice versa, with pins 64 as the pivot points. The primary purpose of having the bar 62 movable toward and from the rolls is to permit the levers 27 to be 30 inserted, removed or adjusted readily and easily. Primarily an adjustment of the resilient pressure of the rollers 20 against the cylinder 4 is obtained by rotating the eccentric shaft 37.

35 Suitable leaf springs 69 are attached to the end of each arm member 27, to hold the selvaging rollers resiliently against the platen roll. The leaf springs may be attached to their respective arm members by means 40 of a block 70 secured to one end of the spring, the block being inserted in a slot 71 formed in the end of the arm member, and the block securely held within the slot by a suitable screw 72 penetrating the arm and 45 block. Each leaf spring is of such length as to extend well under the horizontal leg 73 of the angle bar. A block 74 may also be secured to this end of each leaf spring, an adjusting screw 75 penetrating each block 50 and contacting the lower side of the horizontal flange 73 of the angle bar and under which the ends of the springs are confined. Now it is seen that, by unloosening key bolts 68, the angle bar 62 can be swung outwardly so as to uncover the ends of the 55 springs, thus permitting the rollers 20 to be inserted, removed, or adjusted readily and easily. By swinging angle bar 62 inwardly the ends of springs 69 again are confined 60 beneath the flange 73 of the bar.

Means are provided for making bandages of various widths. Arms 27 carrying the selvaging rollers 20 may be positioned at any desired point along the bar by unloosening a screw 76 carried by each saddle mem-

ber 28 and sliding the saddle member to the point desired. A longitudinal groove 77 may be formed in the supporting bar to receive the end of the screws 76. Corresponding adjustments may also be made of the slitting rollers 17. Thus non-raveling strips of various chosen widths may be obtained from the original web roll of fabric operated on.

The operation of the complete slitting and selvaging machine will now be described. The direction of roll rotation and the drive means therefor are diagrammatically illustrated in Fig. 3. A pulley wheel 78 attached to drive shaft 79 is geared to guide roll 6, 75 which is in turn geared to the ironing roll 4. Suitable belting 79 extends around pulley wheel 78, pulley wheel 80 fixed to the shaft 81 of guide roll 16, and pulley wheel 82. The direction of rotation of the various 85 rolls is illustrated by arrows in Figs. 2 and 3.

The slitting rollers 17 press against the bandage gauze material 8 as it moves around the backing or platen roll 4, and severs the 90 bandage material into strips. The selvaging rollers 20 crush and mash the strips at their edges against the backing or platen roll and render these edges non-raveling. The selvaging rollers and the slitting rollers 95 are in tandem relation. It is understood, however, that the pressing operation may be performed before or after the slitting operation, as desired. In the illustrative embodiment shown in Fig. 2, the pressing rollers are arranged to follow the slitting rollers, 100 selvaging the edges of the bandage strips after they have been cut. In any event, the selvaging rollers are so arranged that each forms the adjacent selvaged edges of two 105 adjacent strips.

It is necessary that the surface of the platen roll be hard and firm to form the proper backing for the selvaging rollers. In order to produce an unraveling selvage, the 110 warp and weft threads must be more than pressed together into merely cohering contact, which would be insufficient to prevent separation of the intersections, since any such separation would permit interior threads to pass by and out of the edge of the strip, constituting ravel and fray. The individual threads must be so mashed and crushed that there can be no separation at the intersections, thus positively preventing 115 interior threads from passing out of the edge of the strip to create ravel and fray. The treatment should destroy the tensile strength of the material and create a pulpi-fied condition. The material intermediate 120 the intersections should retain sufficient strength to cause the selvage edge to remain on the strip in ordinary service. The pressure should be firm and uniform, and of such nature as to create the conditions speci- 125 130

fied, and the machine should be adjusted accordingly.

By rotating eccentric cylinder 37 by means of hand crank 55, the supporting bar 29 may be gradually raised, raising all the arms 27 in unison, and pressing the rollers carried thereby more heavily against the fabric. The supporting bar can be raised by this means until such a pressing effect is exerted on the fabric as to produce my non-raveling selvage. Pawl 56 engages ratchet wheel 59 and holds the eccentric cylinder in the position to which it has been rotated, and holds the supporting bar in the corresponding raised position which produces the desired selvaging effect. Leaf springs 69 maintain the pressure of the rollers against the fabric uniform, regardless of any irregularity in the surface of the platen roll or in the fabric itself. The pressure of the individual roller against the platen roll can be fixed by the adjusting screw 75, thus providing for any difference in resiliency of the leaf springs and insuring the effective operation of each and every roller.

To release the pressure effect of the rollers against the fabric, it is simply necessary to lift the pawl 56 and lower the supporting bar 29 by turning crank arm 55.

It is seen that with my selvaging attachment bandages having non-raveling selvages can be produced without additional labor or material, the only additional expense of manufacture being the upkeep, wear and tear of the selvaging attachment, which is practically negligible in computing bandage costs. My superior bandages can, therefore, be produced at practically the same cost as that at which inferior unselvaged bandages can be produced.

While I have shown my selvaging machine associated with the ordinary bandage slitting machine, it is understood that my selvaging device and a suitable backing member associated therewith may be built as a separate and distinct machine apart from the slitting machine, the bandage material passing through each machine separately, within the contemplation of this invention. And, as many changes could be made in the above construction and as many apparently widely different embodiments of this invention, consisting of progressing bandage material between selvaging surfaces to produce unraveling selvages, could be made without departing from the scope thereof, it is intended that all matter contained in the above description or shown in the accompanying drawings shall be interpreted as illustrative and not in a limiting sense.

What I claim is:—

1. In a machine for making surgical bandages, the combination of means for feeding a web of fabric material through the machine, and juxtaposed cutting and crushing

devices for cutting the material and crushing the cut edges to prevent raveling.

2. In a machine for making surgical bandages, the combination of a platen roller, means for feeding a web of fabric material over said roller, and juxtaposed cutting and crushing devices operating against the platen roller for cutting the material and crushing the cut edges to prevent raveling. 70

3. In a machine for making surgical bandages, the combination of means for feeding a web of fabric material through the machine, and a tool, including cutting and crushing devices, for crushing the cut edges to prevent raveling. 75

4. In a machine for making surgical bandages, the combination of a platen roller, means for feeding a web of fabric material over said roller, and a tool, including cutting and crushing devices operating against the platen roller, for cutting and crushing the cut edges to prevent raveling. 80

5. In a machine for making surgical bandages, the combination of means for feeding a web of fabric material through the machine, a cutter and a crusher supported in tandem position on the machine to cut the material and crush the cut edges thereof to prevent raveling. 90

6. In a machine for making surgical bandages, the combination of means for feeding a web of fabric material through the machine, a rotary cutter and a rotary crusher supported in tandem position on the machine to cut the material and crush the cut edges to prevent raveling. 95

7. In a machine for making surgical bandages, a platen roller, means for feeding a web of material over said roller, and a rotary cutter having a dull peripheral cutting edge and a rotary crusher having a dull peripheral crushing edge arranged in tandem position to operate on the web as it passes over the platen to cut the web and crush the cut edges to prevent raveling. 105

8. In a machine for making surgical bandages, the combination of a backing member, means for feeding a web of bandage material to the backing member, means, including a selvaging roller resiliently crushing the material against the backing member, for producing a crushed selvage strip in the bandage material, said crushed strip forming an edge of two finished bandages, and means for moving said rollers to 110 and from said member.

9. In a machine for making surgical bandages, the combination of a backing member, means for feeding a web of bandage material to the backing member, means, including selvaging rollers resiliently crushing the material against the backing member, for producing crushed selvage strips in the bandage material, each crushed strip forming an edge of two finished bandages, 115 120 125 130

- and means for adjusting the crushing force exerted by the rollers on the material.
10. In a machine for making surgical bandages, the combination with a platen roll over which the bandage material is adapted to pass, means, including selvaging rollers resiliently crushing the material against the platen roll, for producing crushed selvage strips in the material, each crushed strip forming an edge of two finished bandages, means for adjusting the crushing force exerted by the rollers on the material and means for moving said rollers into and out of contact with the platen roll.
15. 11. The combination with a backing member over which material to be selvaged is adapted to pass, of means for producing crushed selvage strips in said material, said means including a supporting bar, arms carried by said supporting bar, selvaging rollers carried by said arms, and means for resiliently retaining said rollers with crushing force against the material on said backing member.
20. 12. The combination with a backing member over which material to be selvaged is adapted to pass, of means for producing crushed selvage strips in said material, said means including a supporting bar, arms transversely disposed across said supporting bar and adjustable longitudinally thereon to vary the spacing of the crushed selvage strips, a selvaging roller carried at one end of each of said arms, and means at the other end of said arms for resiliently retaining said rollers with crushing force against the material on said backing member.
25. 13. The combination with a backing surface over which material to be selvaged is adapted to pass, of means for producing crushed selvage strips in said material, said means including a supporting bar, arms transversely disposed across said supporting bar, a selvaging roller carried at one end of each of said arms, resilient means at the other end of said arms for resiliently retaining said rollers with crushing force against the material on said surface, and means associated with said resilient means for adjusting the resilient force applied to said rollers.
30. 14. The combination with a backing surface over which material to be selvaged is adapted to pass, of means for producing crushed selvage strips in said material, said means including a supporting bar, arms transversely disposed across said supporting bar, selvaging rollers carried by said arms, means for resiliently retaining said rollers with crushing force against the material on said surface, and means for adjusting said bar to move said rollers into and out of crushing contact with said material.
35. 15. The combination with a backing surface over which material to be selvaged is adapted to pass, of means for producing crushed selvage strips in said material, said means including a supporting bar, arms transversely disposed across said bar, selvaging rollers carried by said arms, means for resiliently retaining said rollers with crushing force against the material on said surface, and manual means for manipulating said bar to move said rollers into and out of crushing contact with said material and means for locking said bar against movement.
40. 16. The combination with a backing surface over which material to be selvaged is adapted to pass, of means for producing crushed selvage strips in said material, said means including a supporting bar, arms transversely disposed across said bar, selvaging rollers carried by said arms, means for resiliently retaining said rollers with crushing force against the material on said surface, and manual means for manipulating said bar to move said rollers to and from said backing surface and to obtain the desired crushing force of said rollers on said material, and means for locking said bar in the desired position.
45. 17. The method of making bandages from a roll of surgical gauze, which consists in feeding a web of gauze from the roll over a platen roller and cutting the web into bandage strips while it is passing over said roller and immediately crushing the edges of the strip before they pass from said roller to prevent raveling at the edges of the bandages.
- This specification signed this 28th day of May 1928.
- OCTAVE LE CLAIR VALENTINE.
